CANASTA CARD TRAY

Francesco Collura, New York, N. Y.

Application December 7, 1949, Serial No. 6,471

Term of patent 7 years

(Cl. D34—13)

To all whom it may concern:

Be it known that I, Francesco Collura, a citizen of the United States, residing at New York, in the county and State of New York, have invented a new, original, and ornamental Design for a Canasta Card Tray, of which the following is a specification, reference being had to the accompanying drawing, forming part thereof.

Fig. 1 is a plan view of a canasta card tray embodying my new design;

Fig. 2 is a longitudinal sectional view of the same, taken on substantially the plane of line 2—2 of Fig. 1;

Fig. 3 is a side elevation thereof; and
Fig. 4 is an end view of the same.

I claim:

The ornamental design for a canasta card tray, substantially as shown.

FRANCESCO COLLURA.
